UNITED STATES PATENT OFFICE

JOSEPH L. KALLUS, OF BROOKLYN, NEW YORK

DESIGN FOR A TOY DOG

Application filed January 15, 1930. Serial No. 34,136. Term of patent 14 years.

To all whom it may concern:

Be it known that I, JOSEPH L. KALLUS, a citizen of the United States, and resident of the borough of Brooklyn, county of Kings, city and State of New York, have invented a new, original, and ornamental Design for a Toy Dog, of which the following is a specification, reference being had to the accompanying drawing, forming part hereof, wherein--

Fig. 1 is a side elevation of a toy dog illustrating my new design, and Fig. 2 is a front elevation thereof.

I claim:

The ornamental design for a toy dog, as shown.

JOSEPH L. KALLUS,
